US0D1070298S

(12) **United States Design Patent** (10) Patent No.: **US D1,070,298 S**
(45) Date of Patent: ** Apr. 15, 2025

(54) **SHOE**

(71) Applicant: **adidas AG**, Herzogenaurach (DE)

(72) Inventors: **Ulisse Tanzini**, Nuremberg (DE); **Sam Handy**, Cadolzburg (DE); **Moritz Hoellmueller**, Fuerth (DE); **Herisson Redi Ferreira**, Nuremberg (DE); **Muriel Vanessa Jung**, Nuremberg (DE)

(73) Assignee: **adidas AG**, Herzogenaurach (DE)

(**) Term: **15 Years**

(21) Appl. No.: **29/909,740**

(22) Filed: **Aug. 10, 2023**

Related U.S. Application Data

(63) Continuation of application No. 29/889,343, filed on Apr. 11, 2023, now Pat. No. Des. 998,942, which is a continuation of application No. 29/838,720, filed on May 15, 2022, now Pat. No. Des. 986,542, which is a continuation of application No. 29/762,463, filed on Dec. 16, 2020, now Pat. No. Des. 955,703.

(57) **CLAIM**

The ornamental design for a shoe, as shown and described.

DESCRIPTION

FIG. 1 is a perspective view of a shoe, showing our new design.

FIG. 2 is another perspective view of the shoe of FIG. 1.

FIG. 3 is another perspective view of the shoe of FIG. 1.

FIG. 4 is another perspective view of the shoe of FIG. 1; and,

FIG. 5 is a side view of the shoe of FIG. 1.

The areas within the figures partially obscured with translucent shading and surrounded by broken lines represent portions of the shoe that form no part of the claimed design. The broken lines immediately adjacent to the areas with translucent shading form no part of the claimed design.

1 Claim, 5 Drawing Sheets
